William Brown Cleland, Hamilton, Ontario, Canada, assignor to Jordan Wine Company, Ltd., Jordan, Ontario, Canada, a corporation of Canada

Application October 30, 1933. Serial No. 49,596

Term of patent 14 years

To all whom it may concern:

Be it known that I, WILLIAM BROWN CLELAND, a citizen of the Dominion of Canada, residing at Hamilton, in the county of Wentworth, Province of Ontario, Canada, have invented a new, original, and ornamental Design for a Bottle, of which the following is a specification, reference being had to the accompanying drawing, forming part thereof.

Fig. 1 is a front view;

Fig. 2 is a back view; and

Fig. 3 is a side view of the bottle, showing my new design.

I claim:

The ornamental design for a bottle, as shown.

WILLIAM BROWN CLELAND.
